UNITED STATES PATENT OFFICE.

CHARLES F. FRANCISCO, OF SAN DIEGO, CALIFORNIA, ASSIGNOR OF ONE-EIGHTH TO GEORGE GOODWIN, OF SAME PLACE.

CAR-COUPING.

SPECIFICATION forming part of Letters Patent No. 425,166, dated April 8, 1890.

Application filed December 18, 1889. Serial No. 334,146. (No model.)

To all whom it may concern:

Be it known that I, CHARLES F. FRANCISCO, of San Diego, in the county of San Diego and State of California, have invented a new and useful Improvement in Car-Couplings, of which the following is a specification.

My invention is an improvement in car-couplings, and seeks to provide a simple novel construction of automatic coupler which will be simple and strong of construction and easy and certain in operation; and the invention consists in certain novel constructions and combinations of parts, as will be hereinafter described and claimed.

15 In the drawings, Figure 1 is a perspective view of my coupling applied to a car. Fig. 2 is a vertical longitudinal section of the coupling with the coupling devices in uncoupled position. Fig. 3 is a vertical longitudinal section showing the coupling devices in the coupled position. Fig. 4 is a section of the draw-head on about line 4 4 of Fig. 5. Fig. 5 is a section of the draw-head on about line 5 5 of Fig. 4. Fig. 6 is a top plan view, the top plate being removed. Fig. 7 is a detail view of the coupling-dog. Figs. 8 and 9 are perspective views of, respectively, the under and upper sides of the gravity-block. Fig. 10 is a detail view of the lock-piece, and Fig. 11 is a detail view of the lever for operating such lock-piece.

The draw-head A may be secured to the car in any suitable manner, and is provided with the throat or link mortise *a*, opening out of its front end, the mouth being suitably flared to insure the proper entry of the link. At its forward end the base-wall of the draw-head is formed centrally with a notch B, on opposite sides of which are hook-like portions *b*, the rear sides of which are in a measure undercut to form hooks and stop-like portions for the trunnions of the coupling-dog. These portions *b* also form a fulcrum for the link and abutments for engagements by the projecting portions of the coupling-dog trunnions in the operating of such parts, as more fully described hereinafter.

The bottom wall of the draw-head is formed in alignment with notch B, with a slot C for the passage of the locking-arm of the coupling-

dog, at the front end of which slot is formed, at D, a bearing for engagement by the hook on said locking-arm, as will be more fully described. Ledges or supporting-surfaces E are provided on opposite sides of slot C and in rear of the hooks *b*, such ledges being arranged to support the trunnions of the coupling-dog and being inclined at *e* downward toward their rear ends to cause the dog to move rearwardly as the link is withdrawn.

At the rear of the ledges E, I form abrupt stop-shoulders F to limit the rearward movement of the dog, and above and in rear of such shoulders F, I form a bearing-surface G, which inclines downward toward its front end and serves to support and throw the gravity-block forward in the operation of the device. An opening *h*' is formed through the top wall of the draw-head near its front end, such opening serving for the passage of the vertically sliding lock.

The draw-head is provided on its upper side with a top casing H, having the opening *h*' in its floor or bottom and having its top inclined upward from front to rear, and at the rear of which is formed an opening or offset *h*. The top plate or cover I of this casing projects rearwardly beyond the same to form a rain and snow guard, and is preferably arranged, as shown, so it may be conveniently removed when desired and can be rigidly secured. To this end I form at the front end of the top casing an undercut or hook-like bearing at *i* for the front end of the top plate, and secure the rear end of the said plate by a bolt, as shown; but while this manner of securing the top plate may be preferred, it is manifest that it may be secured in other desired manner. Through the rear end of the top casing I form an opening J for the passage of the rod, chain, or other operating-connection for the lock-operating lever, so that in case two draw-heads are bumped hard together or ride up one on the other the chain or connection will drop in the offset or opening and be protected from damage. This offset construction also forms a receiver for the slack of the connecting-chain. Within the top casing I form in its side walls a pair of guide-channels K and a pair of channels L, the former

K serving to receive the guide-ribs of the slide-lock and the latter L to receive the trunnions of its operating-lever.

It will be noticed in the following description of the several working parts of the coupling that none of them are held rigidly to the draw-head; but all are supported so as to operate freely, and so they can be quickly applied to or removed from the draw-head, 10 and yet will be properly held in operative position.

The coupling-dog M is formed with three arms 1, 2, and 3, the arm 1 being formed to secure the link, the arm 2 being a stripping-arm and arranged for engagement by the link as the latter enters the draw-head, and the arm 3 being a locking-arm to prevent the upward movement of the dog when in coupled position. To this end the arm 3 has a hook 15 4, which in the coupled position of the dog engages the bearing D of the draw-head and locks the dog from upward movement. When uncoupled, the arm 1 rests in the notch B, the arm 2 extending in proper position to be engaged by the entering link, which tends to turn the dog to coupled position, the arm 1 entering and passing up through the link and being engaged and held by the lock, presently 20 described. It will be noticed that the arm 3 25 of the dog projects in diametrically-opposite directions to arm 1.

In operation the dog rocks and slides, and, so far as I am informed, it is broadly new in car-couplings to provide a link-securing dog 30 which both rocks on a journal and is capable of sliding. I therefore do not wish to be limited in this feature of my invention to the particular details of construction preferred. In carrying out this feature of my invention 35 I provide the dog with the rigid or fixed trunnions m, which project over and rest upon the ledges E and slide thereon between the hooks b and bearings F, and are free to turn thereon in the rocking of the dog, as will be understood. These trunnions, it will be 40 seen, are non-circular, being widened out at 5 in the direction of arm 2 of the dog, and having projections or portions 6 at a point slightly back from the front edge of the arm 45 1. The purpose of the widened portions 5 is to strike the shoulders F of the draw-head and tend to throw the dog forward as the link enters the draw-head, the under side of such widened portions 5 being inclined, as shown, 50 to insure such end. This widening out of the trunnion and the throwing forward of the dog quickens the turning of the dog and so hastens the passing of the lock by the dog, 55 enabling the use of a shorter link than would be otherwise practicable.

It will be seen that as the link enters the draw-head it will engage the arm 2 and tilt or rock the dog, causing the portion 5 to strike shoulders F and throw the dog forward, 60 the arm 1 being moved up through the link. In the uncoupling of the link, as it draws the coupling-dog to uncoupled position, the pro-

jections 6 strike the hooks b and force the coupling-dog back toward the inclined parts e of the ledges E, down which it slides. It 70 will be understood that as the dog is thrown forward as well as turned by the entrance of the link such construction enables the use of a short link, as only a slight entrance of the link is necessary to turn the arm 1 of the dog 75 past the lock, which secures such arm to hold the link.

The gravity-block N fits in the draw-head and rests upon the inclined surface G in rear of the coupling-dog. This block has its upper side concaved at 7 to facilitate its passage past the lower end of the lock in inserting and removing the block from the draw-head through the mouth of the latter, and the under side of the block is rounded into rocker 85 form, the weight of the block being so disposed that it will tend to rock back toward its rear end. At its front end the block is slotted centrally at 8 or bifurcated to permit the operation of the armed coupling-dog, and 90 its under side has inclines at 9 to facilitate the passage under it of the link, has in rear of such inclines 9 surfaces at 10 to bear upon the arms of the link and hold the outer end of the link elevated, and has in rear of surfaces 10 the inclined surface 11, which bears upon the surface G of the base-wall of the draw-head. It will be understood that this gravity-block fits loosely in the draw-head and slides down by gravity upon the link after 100 it has been pushed up and back by the said link as it enters. The coupling-dog being also loosely fitted in the draw-head, I form such dog and the gravity-block so that each of such parts will serve to secure the other 105 within the draw-head. To this end the arms of the dog are arranged to engage and hold the gravity-block back. Thus in the uncoupled position of the dog arm 2 rests in front of the gravity-block and holds it back, 110 the weight of the block at the same time serving to hold the dog down and in operative position. Now as the link enters the draw-head it strikes arm 2 and pushes such arm back, and also the gravity-block, the link 115 passing under the block. Now as the dog is drawn to uncoupled position by the exit of the link the arm 2 passes up under and to a point in advance of the gravity-block, operating to hold such block back, so that it is impossible to withdraw the block so long as the coupling-dog is in place in the draw-head, 120 while by first removing the dog the block may also be removed.

To secure the arm 1 of the coupling-dog in engagement with the link, I provide a suitable lock N', which preferably is a slide operating through opening h', and having ribs n, which move in the channels K in the top easing. In its rear side the slide has a socket or recess O. The lever P for operating this slide N has trunnions p, which slide and turn in the channels L of the top casing. This lever has an arm Q, the point of which fits in

the socket or recess O, and also an arm R, which may be called the "handle-arm," such arm R curving or inclining forward toward or over the slide, and serving, when such slide is lowered, to prevent any upward jolting or jarring thereof. In effecting this end it will be seen that the relation of the cover of the top casing, the lever-arm R, and slide N', when the latter is lowered, is such that the cover presents the movement of the said arm R by the slide necessary to permit the upward jolting of the said slide. The operating-connection Q', which may be a rod, as shown, a chain, or other suitable construction, connects with arm R, and extends thence through the opening J in the rear of the top casing, and may be connected with a shaft journaled to the car, as shown, or to other suitable operating device, as may be desired. Where desired, a spring may be arranged to bear between the arm R of the lever and the rear wall of the top casing, as shown; but ordinarily the weight of the slide-lock is sufficient to properly operate it and its lever, and the spring may be dispensed with.

In operation the entrance of the link effects the coupling, and the uncoupling may be effected by lifting the slide-lock in the manner described, there being no necessity of the brakeman going between the cars at any time.

Where desired, in case of accident or otherwise, the automatic devices may be removed from the draw-head and an ordinary coupling-pin be dropped through opening h' and engage an ordinary coupling-link.

It will be understood that the engaging-surfaces of the slide-lock and coupling-dog may be slightly dovetailed, as shown, or otherwise formed to enable the convenient application thereto of metal plates to take up the wear on said surfaces. At its lower front edge the slide-lock N' has a hook-like bearing n', which engages under the top wall of the draw-head and operates as a means of preventing the upward jolting of the slide-lock when the latter is in coupled position.

Having thus described my invention, what I claim as new is—

1. In a car-coupling, a locking-dog provided with arms and with trunnions made non-circular in cross-section, whereby to provide projections to engage abutments in the draw-head, substantially as set forth.

2. In a car-coupling, the combination of the draw-head and the armed dog supported to rock and slide therein, the said draw-head being provided with abutting or bearing portions for engagement by the dog as the latter is rocked, whereby the rocking of the dog may effect the sliding thereof, substantially as set forth.

3. In a car-coupling, the combination of the draw-head, the armed dog, the lock for securing such dog in coupled position, and the gravity-block arranged in rear of the said dog, substantially as set forth.

4. In a car-coupling, a gravity-block adapted

to support the link in elevated position, having its under side rounded into rocker shape and having its front end bifurcated and 70 formed to bear upon the arms of the link, substantially as set forth.

5. In a car-coupling, the gravity-block hereinbefore described, constructed with its upper side concave and its under side rounded or curved into rocker form, such curve extending gradually up to the upper face of the block at its rear end, the front end of such block being bifurcated and the under side of the block at its front end being formed to fit 80 upon the arms of the link, substantially as and for the purposes set forth.

6. In a car-coupling having an armed dog and a gravity-block, and in combination with such parts, the draw-head having the front 85 lower wall of its throat provided centrally with a notch for the arm of the dog and with portions on opposite sides of such notch to form a fulcrum for the link, the gravity-block being arranged to bear upon the link in rear 90 of such fulcrum, substantially as set forth.

7. In a car-coupling, the combination, with a draw-head having a throat formed in it and an armed locking-dog, of a gravity-block adapted to move freely in the draw-head and 95 to be engaged by the arms of the dog, and a lock for securing the dog in coupled position, substantially as set forth.

8. In a car-coupling, the combination, with a draw-head, of an armed locking-dog supported to rock and slide, a lock for securing such dog in coupled position, and the gravity-block, substantially as set forth.

9. In a car-coupling, the combination of the draw-head, the armed dog constructed to slide and rock in the draw-head, and a gravity-block operating in the draw-head, the armed dog being adapted to secure the link, and the gravity-block to support such link, substantially as set forth.

10. In a car-coupling, the combination, with a draw-head having a throat and a free gravity-block within the throat that is adapted to rest on a coupling-link, of a rocking and sliding armed dog, one arm of which is adapted to engage and secure a coupling-link when such link is supported by the free gravity-block, substantially as set forth.

11. In a car-coupling, the combination, with a draw-head having a throat-cavity, of a freely-operating gravity-block within the draw-head, an armed sliding and rocking dog, and a vertically-guided locking device that interlocks with the dog, substantially as set forth.

12. In a car-coupling, the combination of the draw-head and the armed dog having its trunnions supported to rock and slide in said draw-head, substantially as set forth.

13. In a car-coupling, the combination of the draw-head having a support for the armed dog, which support inclines downward to its rear end, and the armed dog arranged to rock and slide on said support, the inclined por-

tion of the latter serving to throw the dog backward, substantially as set forth.

14. In a car-coupling, a locking-dog provided with a link-securing arm, and with a 5 tripping-arm for engagement by the entering link, and having trunnions which are widened out in the direction of the tripping-arm of the dog, whereby to facilitate the forward movement of the dog on the entrance of the link, 10 substantially as set forth.

15. In a car-coupling, a coupling-dog having arms and fixed trunnions, the latter being formed with projecting portions arranged to abut portions of the draw-head and throw 15 the dog back on the withdrawal of the link, substantially as set forth.

16. In a car-coupling, a coupling-dog having a link-securing arm, a tripping-arm, and trunnions, such trunnions being widened out 20 in the direction of the tripping-arm, and being provided with projecting portions or shoulders arranged to abut portions of the draw-head and throw the dog back on the withdrawal of the link, substantially as set forth.

25 17. In a car-coupling, a coupling-dog having an arm to secure the link, a tripping-arm for engagement by the link, and a third arm or extension adapted to lock the dog from upward movement in the coupled position of 30 the parts, substantially as set forth.

18. In a car-coupling, the improved coupling-dog herein described, having a link-securing arm, a tripping-arm for engagement by the link, an arm or extension to lock the 35 dog from upward movement in the coupled position of the dog, and having trunnions formed with projections to abut portions of the draw-head and widened out in the direction of the tripping-arm, substantially as set 40 forth.

19. In a car-coupling, the combination of the draw-head having the front lower wall of its throat provided with hook-like portions, the upper sides of which form a fulcrum for 45 the link and the rear sides of which form a stop and abutment for the dog-trunnions, and having in rear of such hook-like portions supporting-ledges which incline downward to their rear ends, and the armed dog having 50 trunnions supported on said ledges, substantially as and for the purposes set forth.

20. In a car-coupling, the combination of the draw-head, the coupling-dog constructed to rock and slide in the said draw-head, having 55 an arm to secure the coupling-link, a tripping-arm for engagement by said link as the latter enters the draw-head, and an arm or extension having a hook to engage a bearing on a portion of the draw-head, whereby to 60 prevent the upward movement of the dog in its coupled position, and a latch or lock for said dog, substantially as set forth.

21. The combination of the draw-head having ledges for the trunnions of the coupling-dog inclined downward toward their rear ends 65 and having a bearing for the gravity-block

inclined upward toward the rear, the dog having its trunnions fitted to said ledge, and the gravity-block supported in rear of such dog and constructed to operate in connection therewith, substantially as set forth.

22. The combination of the draw-head having supporting-ledges for the dog, which ledges incline downward toward their rear ends, and having at the forward ends of such ledges hook-like portions, and provided in its bottom with a slot or opening, and the dog having an arm to secure the link, a tripping-arm for engagement by the link, and a holding-arm arranged to operate in the slot of the 80 draw-head and to hold the dog down, and having trunnions formed with widened portions to facilitate the forward movement of the dog when it is turned back and with shoulder-like projections or portions to engage the 85 hooks at the front of the ledges when the dog is turned forward, substantially as set forth.

23. In a car-coupling, the combination of the draw-head having a throat or link mortise, 90 the dog journaled loosely within said throat, and the gravity-block fitted loosely in the throat, the dog being provided with an arm to receive the bearing or weight of the gravity-block, and all being substantially as described, 95 whereby both the dog and block serve to hold each other in the draw-head, substantially as set forth.

24. In a car-coupling, the combination of the draw-head, the armed coupling-dog constructed to secure the link, the lock sliding vertically in the draw-head and arranged to secure the dog in coupled position, and the lever for operating said lock, substantially as 100 set forth.

25. In a car-coupling, the combination, with the coupling-dog and the sliding lock-bar arranged to secure such dog and having a mortise or socket, of the lever for operating said lock, such lever having one of its arms extended into the socket or mortise of the lock-bar, substantially as set forth.

26. In a car-coupling, the combination of the draw-head, the armed coupling-dog constructed to secure the link, the lock-bar arranged to slide in the draw-head, and the lever for operating such lock-bar, said lever being journaled loosely in the draw-head and having one arm connected with the lock, substantially as set forth.

27. The combination of the draw-head having the top casing, the armed coupling-dog, the sliding lock guided in said top casing into position to engage the coupling-dog, and the lever, also supported in said top casing and 125 arranged to engage and operate the sliding lock, substantially as set forth.

28. In a car-coupling, the combination of the draw-head having a top casing, the armed coupling-dog, the sliding lock, and the lever for operating such lock, said lever and lock being supported in the top casing and the lat-

ter being formed with its upper side inclined upward from front to rear, substantially as set forth.

29. In a car-coupling, the combination of 5 the sliding lock-bar, the double-armed lever for operating the same, one arm of such lever being engaged with the lock-bar and its other arm being curved or extended upward and forward, and the casing receiving said lever 10 and lock, having its top plate or cover arranged close to the upwardly-extended arm of the lever, whereby to lock the sliding lock in the coupled position of the parts, substantially as set forth.

15 30. In a car-coupling, the combination of the draw-head having a top casing formed with channels in its side walls for the ribs of the slide-lock and for the trunnions of the lever, the slide-lock having guide-ribs sliding 20 in one pair of said channels, and the lever having its trunnions supported in the other pair of channels and having one of its arms

engaged with the sliding lock, all substantially as set forth.

31. In a car-coupling, the combination of 25 the draw-head having a top casing and formed with an opening or offset at the rear end of such casing, the coupling-dog, the lock for said dog, arranged in such casing, the lever for operating such lock, also arranged in the 30 casing, and the operating-connection secured to said lever and extended through the rear wall of the top casing, substantially as set forth.

32. In a car-coupling, the combination of 35 the armed coupling-dog, the gravity-block arranged in rear of said dog, the sliding lock, and the lever arranged to operate said lock, substantially as set forth.
